UNITED STATES PATENT OFFICE.

EMMA BETTINGER, OF BOONVILLE, INDIANA.

HOSE-SUPPORTER.

1,362,556.

Specification of Letters Patent. Patented Dec. 14, 1920.

Application filed September 14, 1917. Serial No. 191,380.

To all whom it may concern:

Be it known that I, EMMA BETTINGER, a citizen of the United States, residing at Boonville, in the county of Warrick, State of Indiana, have invented certain new and useful Improvements in Hose-Supporters; and I do hereby declare the following to be a full, clear, and exact description of the invention, such as will enable others skilled 10 in the art to which it appertains to make and use the same.

This invention relates to hose supporters and is particularly designed for use by women. As is well known to those skilled 15 in the art, the tearing of hose by the ordinary arrangement of hose supporters is due to the fact that when the wearer is in seated position the front edge of the hose is nearer to the waist line than the back edge while when the wearer erects herself, 20 the front edge moves away from the waist line while the rear edge moves toward the waist line. Therefore, if with the usual arrangement of hose supporters attached to 25 the front and rear edge portions of a corset, the elastics are under proper tension to support the hose when the wearer is erect, the elastic of the front supporter is too loose and the elastic of the rear supporter too 30 tight when the wearer is seated. This excessive tightness of the rear supporter tears the hose at the rear end if the front supporter is sufficiently tight to properly hold the hose when the wearer is seated, the pull 35 is so increased when the wearer stands up, as to tear the hose.

It is the object of the present invention to provide an arrangement in which the stocking engaging members while having 40 individual elastics, will both be positioned directly below the hip joint of the wearer. Then as the wearer sits and stands, the upper ends of the elastics being practically at the hip joint, swing substantially at the 45 hip joint. Now the upper edge of the hose does not vary its position with respect to the hip joint as it does with respect to the waist line and hence the pull on the two elastics does not change and as a result, 50 tearing does not occur.

In the drawings:

Figure 1 is a partial side view of a human figure showing the device in use,

Fig. 2 is a front view of the device,

55 Fig. 3 is a rear view thereof, and

Fig. 4 is another side elevation showing the device upon a sitting figure.

Referring more particularly to the drawings, 1 represents a band of flexible material which is adapted to go around the waist, 60 the band having its ends meeting at the back, where they are laced, clasped, or otherwise suitably fastened. Where clasps are used, they are secured to the ends of a number of longitudinally extended strips of 65 tape 2 which are sewed inside of the belt or band 1, to prevent stretching, and also preserve the necessary degree of shaping required to make the device a waist fitting garment.

The belt 1 is comparatively wide, so as to well cover the small of the back, and also the abdominal portion of the body, and at the sides over the hips is downwardly elongated in comparatively wide tabs 3. These 75 tabs 3 are not only wide enough so that their ends lie forwardly and rearwardly of the hip joint, but are also long enough that their lower ends extend slightly below the hip joint.

Each corner of the tabs 3 has secured thereto the elastic straps 4 and 5 carrying the clasps 6 and 7 which may be of any approved type, and are thereby so positioned that when vertically suspended they will 85 engage the top of the stocking to the front and the rear of a vertical line dropped from the hip line.

The supporter as described when fitted about the wearer's waist securely and comfortably supports the hose, when the wearer is in a standing position, as shown in Fig. 1. When the wearer assumes a sitting position, the forward edges of the tabs 3 swing forwardly each upon the axis which coincides 90 with the hip joint, and in substantial alignment therewith the elastic 4 will also swing forwardly. As each tab 3 swings forwardly, it tends to fold upon a line midway between the elastics and passing substantially through the hip joint of the wearer, as clearly shown in Fig. 4. This causes the longitudinal axes of the elastics 4 and 5 to converge somewhat more sharply than they do when the wearer is erect as shown in 105 Fig. 1. When the tabs swing forwardly, as when the wearer is seated, as shown in Fig. 4, the continuation of the axes of each side pair of elastics intersect practically at the hip joint. Thus, as the wearer swings 110

- her legs forwardly and rearwardly of the vertical position shown in Fig. 1, the stocking engaging members 6 and 7 oscillate about the hip joint as a pivot and consequently there is practically no change in the tensions of the elastics and no jerking on the stockings with consequent tearing of the stockings and discomfort. Upon reference to Fig. 1 it will be noted that the members 6 and 7 are initially engaged with the stocking so that when the wearer stands erect the elastics converge substantially to the hip joint. Thus, the hose are properly and comfortably secured at all times.
- 15 The supporter, by its structure may be worn without the consciousness of the wearer, and provides an adequate substitute for the supporters usually carried by corsets for the use of those women and young girls 20 who do not wear corsets. Furthermore, the device acts, to a certain degree as a substitute for corsets in the supporting effect which it has upon a wearer's waist line.
- What I claim as my invention is:—
- 25 A hose supporter consisting of a belt adapted to fit with its upper edge above the hip joint of the wearer and having at each side a tab that depends to an extent

sufficient to lie with its lower edge slightly below the hip joint of the wearer, the lower edge of each tab being of sufficient length to extend slightly forwardly and rearwardly from a vertical line dropped from the hip joint of the wearer when erect, a pair of elastic strips secured to the lower edge portion of each tab in position to depend at opposite sides of a vertical line dropped from the hip joint of the wearer, each tab between the points of attachment of the elastic strips being foldable under the influence of bringing together of the upper end portions of the elastic strips, whereby the longitudinal axes of each pair of elastic strips may intersect at all times at a point substantially in the continuation 45 of the axis of the hip joint of the wearer, whereby to support hose with substantially constant pull in different bodily positions of the wearer.

In testimony whereof, I affix my signature in the presence of two witnesses.

EMMA BETTINGER.
